UNITED STATES PATENT OFFICE.

EDWIN H. SMYTHE, OF HUBBARD WOODS, ILLINOIS, ASSIGNOR TO WESTERN ELECTRIC COMPANY, INCORPORATED, OF NEW YORK, N. Y., A CORPORATION OF NEW YORK.

TELEPHONE-CALL-DISTRIBUTING SYSTEM.

1,330,220.

Specification of Letters Patent. Patented Feb. 10, 1920.

Application filed March 27, 1918. Serial No. 224,943.

To all whom it may concern:

Be it known that I, EDWIN H. SMYTHE, a citizen of the United States, residing at Hubbard Woods, in the county of Cook and State of Illinois, have invented certain new and useful Improvements in Telephone-Call-Distributing Systems, of which the following is a full, clear, concise, and exact description.

10 This invention relates to a telephone call distributing system of the type in which the calls originated by the telephone lines of the exchange are automatically distributed to the operators' positions that are available for receiving them. In complex systems of this character, abnormal conditions sometimes arise that tend to prevent the proper and prompt extending of the circuits of calling lines to the operators' positions. It is 15 the principal object of this invention to provide an organization in which such abnormal conditions, when they arise, will be taken care of and prevented from interfering with the proper operation of the system.

20 Generally stated, the present system provides a plurality of operators' positions each equipped with a number of plug-terminated connecting circuits for completing connection with called subscribers' lines. The connection between these connecting circuits and the calling subscribers' lines is effected through the medium of a number of finder circuits each of which has an automatic switch at one end for finding and connecting 25 with any subscriber's line that may be calling, and an automatic switch at the other end for selecting an available operator's position, and then connecting with an idle connecting circuit at that position. The selection of an available operator's position is 30 controlled by operator's selecting apparatus common to all of the finder circuits and all of the operators' positions.

In the normal operation of the system the 35 potential which identifies any of the lines as a calling line is automatically withdrawn when the finder circuit makes connection with that line.

If through any fault of the apparatus the 40 potential is not immediately withdrawn, it may result in the rapid tying up of all of the line finders and cord selectors serving the group of lines in which the abnormal line terminates.

45 In accordance with the present invention

it is proposed to provide an arrangement for preventing the operation of more than one line finder and its corresponding cord selector when such an abnormal condition as that above described exists.

The preferred embodiment of the system of the invention is illustrated in the accompany diagrammatic drawings in which Fig. 1 shows two groups of lines with two line finder switches for making connection therewith, together with the associated circuits and apparatus through the medium of which the lines control the switches; Fig. 2 shows one finder circuit complete, and enough of two other finder circuits to illustrate the relationship between them; Fig. 3 shows two cord selector switches of one frame with their associated selection controlling apparatus and circuits, together with similar apparatus and circuits for the 75 cord selector switches (not shown) of another frame; and Fig. 4 shows the position apparatus and one of the connecting cord circuits of one operator's position and indicates the position apparatus and a connecting cord circuit of another position, also one of the called lines with which the cord circuit may be connected. The figures taken together, and arranged side by side in the order indicated by the lines that extend to 80 the margins of the sheets, illustrate as much of a complete organization as is necessary to gain an understanding of the construction and mode of operation of the system.

Two telephone lines are indicated in each 90 of the two groups shown in Fig. 1, it being understood that each group may comprise a large number of such lines. The practice is to give the finder switch brushes access to the terminals of five hundred lines, these 95 lines being arranged in ten groups of fifty lines each. Each of the lines has associated with it at the central office a line relay 12, and a cut-off relay 11. Each line is also provided with one or more spring jacks 14 100 by means of which connection may be made with the line when it is a called line. The lines represented as calling lines in Fig. 1 and the line shown as a called line in Fig. 4 may be lines of the same sort, similarly 105 equipped and located at the same exchange; or the lines may be located at different offices. In the present instance, the called line shown in Fig. 4 is indicated as being provided with connections by means of which 110

it may have control over finder switch mechanism in the manner illustrated in connection with the lines of Fig. 1. Each group of lines, LG and LG', has associated with 5 it certain group apparatus consisting of two relays 19 and 24, a common protective relay 250, and a timing sequence switch 100. There is also provided apparatus common to 10 all of the line groups, comprising the relays 22, 23 and 33.

The groups of lines have access to groups 15 of connecting circuits through the medium of finder circuits F, F', and F², which terminate upon the brushes of pairs of finder switches of which two sets, LF and CS and LF' and CS', are shown. Each of the 20 groups of connecting circuits is associated with a particular operator's position, of which the apparatus of one is shown at O and the apparatus of the other is partially 25 shown at O'. In the particular system illustrated, it is the practice to provide each operator's position with twenty-five connecting circuits extending to multipled groups 30 of terminals upon the cord selector switches, and to give the brushes of each cord selector switch access to the terminals of twenty such groups of connecting circuits. But one of the connecting circuits is shown complete, 35 the other connecting circuits in the associated group and in the other groups being similarly organized and connected. Multiple connections of the connecting circuit with the terminals of the cord selector switches are shown in the case of the 40 connecting circuit that is completely illustrated; and in like manner multiple connections of the telephone line with the terminals of the line finder switches are shown in the case of 45 the line that extends from station A. The multiple connections that exist between corresponding sets of switch terminals and the other connecting circuits and telephone lines are omitted to avoid confusing the drawing.

50 A number of groups of cord selector switches like the group illustrated in Fig. 3 may have access to the same groups of connecting circuits and their corresponding operators' positions. This is indicated in Fig. 3. Each of the groups of cord selector switches has associated with it certain selection controlling apparatus, that associated 55 with the cord selector switches shown in Fig. 3 appearing under the caption "Frame 2", and that associated with the cord selector switches of the other group that is not shown appearing under the caption "Frame 1". The selection controlling apparatus for each frame or group of cord selector switches 60 comprises a set of relays 77, 93 and 94 for each operator's group, CG, CG', to which the cord selector has access, and a group of relays 52, 54, 55, 61, 63 and 254 common to all of the first mentioned groups.

65 As the line finder switches LF and LF',

and the cord selector switches CS and CS' in themselves are not novel, they are shown merely diagrammatically. These switches may be substantially like the switch illustrated and described in the patent to James 70 L. McQuarrie, No. 1,177,044, issued March 28, 1916. The line finder and cord selector switches are alike in all substantial respects. Each comprises a longitudinally movable shaft 1 carrying as many sets of brushes 2 as 75 there are groups of stationary terminals to be engaged. To move the shaft up, an extension at the lower end of the shaft is brought into engagement with the constantly rotating power member 3 by means of an 80 idler wheel operated by the up-drive magnet 32; and to move the shaft down, the extension is brought into engagement with the power member 4 by means of an idler wheel operated by the down-drive magnet 62. 85

Normally the brushes of each of the sets 90 2 are held apart, so as to clear the associated terminals, by means of a separating cam 5 located between the innermost brushes of the set. The cam 5 is rotatably mounted, 95 and when rotated in one direction, releases the brushes and permits them to engage the associated terminals. The tripping or releasing of the brushes is controlled by a number of trip-magnets 16, 17. Each of 100 these when energized rotates an associated trip rod 6 that extends transversely to the switch shafts 1 and carries as many tripping yokes 7 as there are finder switches in the group. The trip rod, in rotating, brings 105 all of its tripping yokes 7 into position to operate the brush controlling cams 5 of the corresponding sets of brushes on all of the switches, so that whichever of the finder switches is caused to move up has that set 110 of brushes tripped that corresponds with the particular trip magnet 16, 17, that is at the time energized. When the finder switch that has been in use is returned to its normal position, any of the associated controlling 115 cams 5 that has been tripped is engaged and rotated in a reverse direction to separate its switch springs again and thus render them inactive.

Each of the line finder and cord selector 120 switches has associated with it a commutator 8 which comprises a number of stationary commutator segments and a set of movable brushes carried at the top of the switch shaft 1 and coöperating with the stationary segments. This commutator serves to make and 125 break a number of controlling circuits in the various stages of the upward movement of the switch shaft.

For controlling the circuits of the organization, there are employed a number of sequence switches which are shown at different points and are designated 100, 200, 300 and 400, respectively. These sequence switches may be of the type disclosed in 130

Patent 1,127,808 issued February 9, 1915, to Reynolds and Baldwin. Each consists of an electro-magnetically controlled motor or driving mechanism and a number of associated switch cams. The switch cams associated with each of the sequence switches 100 are designated 101 to 103 inclusive; those associated with each of the sequence switches 200 are designated 201 to 224 inclusive; those associated with each of the sequence switches 300 are designated 301 to 304 inclusive; and those associated with each of the sequence switches 400 are designated 401 to 413 inclusive. To each of the contacts associated with the various sequence switch cams are applied certain numerals. These numerals in the case of the cams 101, 201, 301 and 401 indicate the only positions of the associated sequence switch in which these particular contacts are open; the numerals applied to all of the other contacts of each sequence switch indicate the only positions of the particular associated switch in which the associated contacts are closed.

25 The sequence switches 100 merely act as timing switches and have only one resting position. The resting positions of the other sequence switches, and the stages of operation with which these positions are associated, are as follows:

Sequence switch 200.

1. Normal.
2. Awaiting starting circuit.
3. Awaiting starting circuit release.
4. Hunting calling line.
5. Awaiting preceding finder circuit.
6. Awaiting operator's selecting circuit.
7. Releasing operator's selecting circuit.
8. Hunting cord circuit.
9. Hunting cord circuit.
14. Talking.
15. Line finder at tell-tale.
16. Cord selector at tell-tale.
- Line finder return.
17. Cord selector return.

Sequence switch 300.

1. Awaiting a call.
4. Position vacant.
17. Position busy.

Sequence switch 400.

1. Normal.
7. Listening in.
15. Listening out.

The manner in which the system is organized will appear from the description of its operation which follows. It will be assumed that the subscriber at station A initiates a call. When the telephone receiver is taken from the switchhook, a circuit is closed that extends by way of both windings of the line relay 12 and both limbs of the telephone line, and is completed in the contacts of the

switchhook at the subscriber's station. The flow of current in this circuit energizes the line relay 12, which in operating applies a ground to the conductor 18 through right-hand front contact and armature of relay 12 and left-hand back contact and armature of relay 250. This causes current to flow from battery through the winding of the relay 19, sequence switch contact 103 (18 $\frac{3}{4}$ to 1 $\frac{1}{4}$), conductor 18 and ground through the contacts of the operated line relay 12 and the left-hand back contact of relay 250. The relay 19 attracts its armature and closes a circuit that extends from battery through the right-hand winding of the associated relay 24, front contact of relay 19, back contact of relay 22 and lower armature and back contact of relay 23 to ground. Relay 24 operates and closes in its left-hand front contact a circuit that extends from battery by way of the winding of the associated group trip magnet 16 and the left-hand winding of the relay 24, in parallel, to the front contact of that relay, and thence by way of conductor 58, the winding of the relay 22, and the lower armature and back contact of the relay 23 to ground.

Current flowing in the circuit traced above operates the trip magnet 16 of the group in which the calling line is located, locks up the relay 24 of the associated group and operates the relay 22 common to all of the groups. The trip magnet 16 rotates its associated trip rod to bring all of the yokes into position to trip the corresponding set of brushes 100 of whichever of the line finder switches is started. The group relay 24 breaks, in its left-hand back contact, the circuit of the conductor 58 to the corresponding relays 24 of the succeeding groups of the series.

The relay 24, in its right-hand front contact, also completes a circuit that extends from battery through the motor magnet of the sequence switch 100, and contact 102 (18 $\frac{3}{4}$ to 1 $\frac{1}{4}$) of that switch. In moving out of position 1, sequence switch 100 closes its contact 101 and opens its contact 103. As contact 101 is closed in all positions excepting position 1 of the sequence switch, the switch is caused to make one complete rotation; and as contact 103 of the sequence switch is open in all positions excepting positions 18 $\frac{3}{4}$ to 1 $\frac{1}{4}$, the conductor 18 is held open while the sequence switch is making its revolution and until it gets back to position 1. The time required by the sequence switch to make one complete rotation is so regulated as to be greater than that occupied by the line finder switch in finding the terminals of any calling line. The action, therefore, is such as to interrupt the group conductor 18, and hold it open until after the line relay 12 of the calling line has been released as a result of the finding of that line.

The relay 22, common to all the groups, 130

in operating opens in its back contact the circuit of the conductor 57, which extends serially through the back contacts of the relays 19 of the various groups. As this conductor 57 is the path over which the relay 19 of any group serves to effect the initial energization of the associated relay 24 and the operation of the corresponding trip magnet, the interruption of this conductor insures the operation of only one trip magnet and the tripping of only one set of brushes on a started line finder switch.

The common relay 22, when it operates, applies ground to the starting conductor 29 to start a finder switch hunting for the calling line. The starting conductor 29 has branches extending to like sequence switch cams 206 of all of the finder circuits terminating upon the line finders that have access to the calling line. But, for reasons which will hereinafter be explained, the sequence switch 200 of only one of these finder circuits is standing in its 2 position. Assuming that this is the sequence switch of finder circuit F, when the relay 22 is actuated by the calling line, as already described, a circuit is completed that extends from battery through the left-hand winding of relay 30, sequence switch contacts 206 (2), conductor 29, front contact and armature of starting relay 22, lower armature and back contact of relay 23 to ground. The right-hand winding of relay 30 is at this time also included in parallel with the left-hand winding of the relay in the energizing circuit, the parallel branch being from battery through resistance coil 56, sequence switch contact 217 (2 to 9), right-hand winding of relay 30, sequence switch contacts 220 (2) and (1 to 13), thereafter joining the conductor that extends from the left-hand winding of relay 30, and to ground over the circuit already traced. The effect of this is to give the relay 30 the benefit of the energizing action of both windings.

As a result of the closure of the circuit traced above, the relay 30 is energized and closes a circuit that causes the associated sequence switch 200 to move out of position 2. This circuit extends from battery through the motor magnet of the sequence switch 200, sequence switch contact 202 (2), right-hand front contact and armature of relay 30, sequence switch contact 208 (2 to 7), conductor 79, commutator segment M of the associated cord finder switch CS, and to ground by way of the brush that is in engagement with this commutator segment. Relay 30, in attracting its armatures, also closes a locking circuit for itself that extends from battery by way of the resistance coil 56, sequence switch contacts 217 (2 to 9), the right-hand winding of the relay 30, sequence switch contacts 216 (2 to 4) and (2 to 9), 65 front contact and left-hand armature of the

relay 30, and armature and back contact of the relay 37 to ground.

As a result of the closure of its motor magnet circuit in the right-hand front contact of the relay 30, the sequence switch 200 moves out of position 2 and comes to rest in position 3. In position 3 of the switch, a circuit is closed that extends from battery by way of the up-drive magnet 32 of the corresponding line finder switch LF, conductor 59, sequence switch contact 207 (3 to 4), front contact and right-hand armature of relay 30, sequence switch contact 208 (2 to 7), and to ground by way of conductor 79 and the commutator segment M and associated brush of the corresponding cord finder CS. The energization of the up-drive magnet 32 starts the upward movement of the corresponding elevator rod with its associated sets of brushes. At the outset of the upward movement of the elevator rod, all of the brush trip levers are moved past the corresponding trip yokes. The only trip magnet that is energized in this case is the magnet 16 which corresponds with the group in which the calling line is located; and, consequently, the only trip yoke in position to engage a trip lever on the elevator rod is the one which controls the brushes 40, 41, 42 and 43 that are adapted to engage the terminals of that particular group of lines. This set of brushes, therefore, is released and made operative, and the other sets are held clear of their associated line terminals.

As soon as the set of brushes corresponding with the calling line is tripped, the group apparatus, by means of which the lines control the brush tripping and line finder starting operations, may be returned to its normal condition. The first step in this restoring operation is effected by the closure of a circuit which is completed by way of the K segment of the line finder commutator immediately after the brushes are tripped. This circuit extends from battery in parallel branches through the relays 23 and 33 (see Fig. 1), conductor 26, sequence switch contact 209 (2 to 3), conductor 68 and to ground by way of the K segment of the line finder commutator and its associated brush. The energization of the relay 23 interrupts, at the lower back contact of that relay, the previously described circuit that has up to this time maintained the energization of the trip magnet 16, the group relay 24 and the common starting relay 22. Relay 23, at its upper front contact, closes a locking circuit for itself and the associated relay 33 that extends by way of conductor 25 and the sequence switch contacts 210 (2 to 1) of all of the finder circuits in series, to ground at a point beyond the last switch of the series.

As has already been stated, normally there is only one of the finder circuits with its

sequence switch in position 2 awaiting the receipt of a call. When the call comes in, this sequence switch is immediately moved to position 3, in the manner described above. 5 Therefore, at this stage of the operation, the sequence switches of all of the finder circuits are in position to close their contacts 210. The locking circuit for the relays 23 and 33 is, therefore, held closed until another one of the finder circuits has its sequence switch moved into position 2. This is accomplished by relay 33, which, in operating, applies a ground to conductor 28 to move the sequence switch of another finder circuit 10 out of position 1 and into position 2, and which also applies a ground to the conductor 27 to move the sequence switch of the appropriated finder circuit out of position 3.

Assuming that the sequence switch of 20 finder circuit F' is in position 1 and that the sequence switch of finder circuit F' is in some position between 4 and 17, that finder circuit being assumed to be in use, the operation of the relay 33 completes the following 25 circuit: from battery, through the motor magnet and contacts 203 (1) of the sequence switch of finder circuit F', contacts 211 (1) of the same sequence switch, contacts 211 (3 to 17) and (4 to 17) of the sequence switch 30 200 of finder circuit F', contacts 211 (3 to 17) and (3 to 3 $\frac{1}{2}$) of the sequence switch 200 of finder circuit F, conductor 28, lower contact and armature of the relay 33 to ground. This causes the sequence switch 35 of finder circuit F' to move into position 2.

If by any chance the sequence switch of 40 finder circuit F' should fail to be moved into the call-awaiting position 2 when the relay 33 operates, it will be moved into that position when the sequence switch of the appropriated finder circuit F moves into position 5 at a slightly later stage in the operation. The circuit by which this result would, under the circumstances, be accomplished 45 extends from battery through the motor magnet and contact 203 (1) of the sequence switch of finder circuit F', contacts 211 (1) of that sequence switch, sequence switch contacts 211 (3 to 17) and (4 to 17) of finder circuit F' (assumed to be in use), and thence by way of contacts 222 (5 to 1) of 50 all of the finder circuit sequence switches in series to ground. In other words, at any time that the finder circuit sequence switches 55 are all standing in position 1 or in position 5 and beyond, a ground is applied by way of the 222 cams in series that moves one of the switches into position 2, and thus places the associated finder circuit in its call-awaiting condition. The sequence switch of 60 finder circuit F is moved out of position 3 by the closure of a circuit that extends from battery through the motor magnet and contacts 203 (3) of the sequence switch of that circuit, conductor 27 and upper contact and

armature of relay 33 to ground. As soon as the sequence switch of finder circuit F' moves into position 2, it opens at its contacts 210 the circuit by way of conductor 25 which has been maintaining relays 23 and 33 energized, and these relays release their armatures. Relay 23, in releasing, reconnects to ground the circuit which extends in branches 57 and 58 through its various sets of group relays, thus again giving 70 75 the groups access to the starting circuit.

At this stage of the operation of the system, the sequence switch of the appropriated finder circuit F is in position 4, and the elevator rod of the associated line-finder LF 80 is moving up with the set of brushes tripped that corresponds with the group in which the calling line is located. As the tripped brushes rise, they come into engagement successively with the sets of contacts corresponding with the different lines of the group. At the instant of engagement of the brush 43 with the terminal 47 of each line, the test relay 37 of the finder circuit is connected with local conductor 253 of that 90 line. This local conductor has two branches, one or the other of which is closed, depending upon the condition of the line relay 12 of the associated line. If the line relay is inert, as it is when the line is not calling, 95 or when the line has been connected with and its cut-off relay operated, the local conductor 253 of the line is connected with ground by way of an identifying device 252 and a relatively low potential battery. If 100

the line relay 12 is energized, as it is when the line is calling and is not connected with, the local conductor 253 of the line is connected with ground by way of the left-hand armature and front contact of relay 12, 105 right-hand back contact and armature of the protective relay 250 common to a group of lines, the energizing winding of this relay, and a relatively high potential battery 251. Therefore, as the elevator rises and the brush 110 43 engages the corresponding terminal 47 of each of the lines of the group in which the calling line is located, a circuit is completed as each line terminal is engaged that extends, either by way of the low potential 115 battery, the device 252, and the left-hand back contact and armature of relay 12 to the local conductor 253 of the line; or by way of the high potential battery, the winding of common relay 250, the right-hand 120 armature and back contact of that relay, and the left-hand front contact and armature of relay 12 to the local conductor 253, and thence by way of line terminal 47, brush 43, conductor 51, finder sequence 125 switch contacts 224 (1 to 8) and (2 $\frac{1}{2}$ to 4), and winding of relay 37 to ground.

The relay 37 is so adjusted that it will respond only to the current flow produced in the circuit by the high potential battery, 130

and not to that produced by the low potential battery. As the line relay 12 of the calling line is energized, thus connecting the high potential battery to the associated local 5 conductor 253, the test relay 37 responds when the brush 43 engages the terminal 47 of the calling line. The response of the relay 37 causes that relay to interrupt in its back contact the previously traced circuit by 10 way of the left-hand armature and front contact of the relay 30, sequence switch contacts 216, and right-hand winding of relay 30, which circuit had been holding the relay 30 locked up from the moment that the relay 15 was first energized upon the receipt of the call. Relay 30 in releasing its armatures breaks its own locking circuit, and also breaks the previously-traced path including sequence switch contacts 208, right-hand armature and front contact of the relay 30, 20 and sequence switch contact 207, over which current has been flowing to energize the up-drive magnet 32 of the line finder. Therefore, the operation of the relay 37 upon the 25 finding of the calling line acts to effect the instant deenergization of the up-drive magnet 32, and thus to stop the brushes upon the terminals of the calling line.

In order that the brushes may always be 30 stopped in registration with the line terminals, the locking circuit of the relay 30 has an alternative path to ground by way of sequence switch contact 215 (2 to 4), conductor 66, the C segment of the line finder 35 commutator and the corresponding brush to ground. The C segment of the commutator is so formed and related to its brush that the connection between the two is interrupted only when the corresponding line brushes 40 on the elevator rod are in engagement with corresponding sets of line terminals. The unlocking of the relay 30 and the consequent stopping of the upward movement of the elevator rod, can therefore occur only 45 when the line brushes are in proper relation to the terminals of the calling line.

When the relay 30 is deenergized, as a result of finding the calling line, it also completes a circuit that extends from battery 50 through the motor magnet and contact 202 (3 to 4) of the finder sequence switch, right-hand back contact and armature of the relay 30, sequence switch contact 208 (2 to 7), conductor 79, and M segment and corresponding brush of the cord selector CS to ground. The closure of this circuit moves the sequence switch out of position 4.

When the finder sequence switch reaches position 4 $\frac{1}{2}$ it closes a path for the flow of current through the cut-off relay 11 of the calling line by way of resistance coil 64, sequence switch contact 212 (4 $\frac{1}{2}$ to 12 $\frac{1}{2}$), conductor 50, brush 42, line terminal 46 and conductor 53. The flow of current in this circuit operates the cut-off relay 11 to disconnect the

relay 12 from the circuit, and that relay in releasing its armatures disconnects the high potential test battery from the local conductor 253 and disconnects ground from the common conductor 18. The disconnection 70 of ground from conductor 18 occurs before the timing sequence switch 100 has completed its cycle of rotation and reconnected conductor 18 with relay 19.

The brushes of the line finder switch are 75 now at rest in engagement with the terminals of the calling line, the sequence switch 200 of finder circuit F is at position 6, the group starting circuit represented by the conductors 57 and 58 and the associated 80 relays 22, 23 and 33 has been released and is in readiness to respond to another calling line, and the sequence switch of another finder circuit has been moved into position 2, and thus brought into operative relation 85 with the starting conductor 29.

When the sequence switch of the finder circuit over which the call is being extended has reached position 6, the finder circuit is brought into operative relation with the operators' selecting circuit. When the finder sequence switch reaches position 6, it awaits the closing of a circuit, the completion of which is dependent upon the condition of the other finder circuits of the associated 90 group. This circuit extends from battery through the left-hand winding of the relay 30, contact 219 (6) of the appropriated circuit sequence switch, contacts 219 (9 to 4) of the sequence switches of the associated 100 finder circuits preceding it in the series, conductor 76, outer armature and back contact of relay 54, and right-hand back contact and armature of relay 61 to ground. A branch path for the energization of relay 30 105 also exists at this time, this branch path extending from battery through resistance 56, sequence switch contacts 217 (2 to 9), right-hand winding of relay 30, sequence switch contacts 220 (6) and (1 to 13), and contact 110 219 (6) of the appropriated finder circuit sequence switch, from which point it extends to ground at the right-hand back contact and armature of the relay 61 over the path already traced. This circuit for the 115 energization of relay 30 is open either in the cam 219 of a preceding finder sequence switch in the series, or in contacts of the relay 54 or 61 as long as any sequence switch of the series is in positions 4 to 9. That is, 120 it is open from the time the line finder switch of any associated finder circuit finds a calling line until the cord finder switch of that circuit has moved far enough to trip the brushes corresponding with the selected 125 operators' position, as will be described. Not until this has occurred will the above traced circuit of the awaiting finder circuit be closed. When the circuit is closed, the relay 30 attracts its armatures and com-

plete a circuit that extends from battery through the motor magnet and sequence switch contact 202 (6 to 7) of the sequence switch 200, right-hand front contact and 5 armature of relay 30, sequence switch contact 208 (2 to 7), conductor 79, and segment M and corresponding brush of the cord selector commutator to ground. The completion of this circuit moves finder sequence 10 switch out of position 6.

When the sequence switch 200 reaches position 6 $\frac{1}{4}$, it closes a circuit that extends from battery by way of the winding of relay 55 (Fig. 3), conductor 71, sequence 15 switch contact 218 (6 $\frac{1}{4}$ to 8), conductor 67, and segment M and corresponding brush of the line finder commutator to ground. The operation of the relay 55 applies ground to the conductors 81 extending to all of the 20 operators' positions. At each of the positions where the operator is at her station and is in readiness to receive a call, the associated relay 91 (Fig. 4) is inert, and the 25 operator's telephone sequence switch 300 is in its 1 position. Consequently at each of such positions, a circuit is closed that extends from battery, through the winding of the associated relay 92, left-hand armature and back contact of relay 91, sequence 30 switch contact 303 (1), conductor 81, armature and front contact of relay 55 to ground. The relay 92 of each awaiting 35 position therefore attracts its armature and closes a circuit that extends from battery, through the front contact and armature of the relay 92 to the conductor 82, and thence to ground by way of the windings of the relays 77 corresponding to that operator's position at the various cord selector frames.

40 When the finder sequence switch 200 reaches position 7, in which position it comes to rest, it closes a circuit that extends from battery through the winding of relay 54, left-hand back contact and armature of relay 61, conductor 73, finder sequence switch contact 218 (7 to 8), conductor 67, and segment M and corresponding brush of the line finder commutator to ground. Relay 54 attracts its armatures and completes a 45 branch of the circuit traced above, which branch extends from conductor 73 by way of the armature and back contact of the relay 63, front contact and left-hand armature of relay 54, right-hand armature and back contact of relay 52, armature and front contact of relay 77, (which relay is 50 energized, as previously described, as a result of the corresponding operator's position being in readiness to receive a call), right-hand back contact and switch spring of relay 93 of the corresponding group, winding of associated relay 94, winding of relay 93, left-hand switch spring and resting contact of relay 93, conductor 83, left- 55 hand back contact and armature of relay

95 at the O operator's position to battery. Upon the closure of the above-traced branch circuit, group relays 93 and 94 are energized in parallel with the relay 54. Relay 93 in operating disconnects its own energizing winding and that of relay 94 from the previously traced path to battery by way of the left-hand back contact and armature of relay 95, and connects them in a path which extends to battery by way of conductor 84 and the winding of the relay 95. This causes the relay 95 also to be energized and to interrupt in its left-hand armature and back contact the path by way of conductor 83 over which the the relays 80 93 and 94 were initially energized.

Relay 94 in operating closes a circuit from battery through the winding of the trip magnet 20 corresponding to the selected operator's position, and to ground by way of 85 the right-hand armature and front contact of the relay 94. This relay also closes a circuit that extends from battery through the winding of the relay 63 and the left-hand armature and front contact of the relay 94 to ground. The relay 63 in operating closes a branch that extends from the conductor 73 (grounded by way of contact 218 (7 to 8) of the line finder sequence switch) through the armature and front contact of relay 63, 95 back contact and armature of relay 254, conductor 72, sequence switch contacts 220 (7) and (1 to 13), and left-hand winding of relay 30 to battery. A branch energizing path for relay 30 also extends from conductor 72 100 by way of sequence switch contacts 220 (7), ring-hand winding of relay 30, sequence switch contacts 217 (2 to 9) and resistance 56 to battery. Relay 30 attracts its armatures and closes a circuit that extends from battery through the motor magnet and sequence switch contact 202 (6 to 7), front contact and right-hand armature of relay 30, sequence switch contact 208 (2 to 7), conductor 79, and segment M and corresponding brush of the cord selector commutator to ground. The closure of this circuit moves sequence switch 200 out of position 7. Furthermore, relay 30 in operating is locked 105 up over a circuit that extends from battery through resistance 56, sequence switch contacts 217 (2 to 9), right-hand winding of relay 30, sequence switch contacts 216 (7 to 9) and (2 to 9), front contact and left-hand armature of relay 30 and armature and back 110 contact of relay 37 to ground.

When the sequence switch reaches position 8 it closes a circuit that starts the upward movement of the brush-carrying rod of the cord selector switch, this circuit extending from battery through the up-drive magnet 34 of the cord finder, conductor 89, sequence switch contact 207 (8 to 9), right-hand front contact and armature of relay 30, sequence switch contact 218 (8 to 9), con- 125 130

ductor 67, commutator segment M of the line line finder and corresponding brush to ground.

- In order to prevent the upward movement 5 of the cord selector switch from being started before the selection of a particular one of the trip magnets 21, 22 has been definitely effected, the circuit of conductor 72, over which the relay 30 is energized when relay 10 63 operates, is placed under the control of a slow releasing relay 254. The energizing winding of the slow releasing relay 254 is in parallel with the energizing winding of the relay 54, and the relay 254 is consequently 15 energized by way of conductor 73 and cam 218 of the finder sequence switch when the sequence switch reaches position 7. The energizing path of the relay 254 is by way of the back contact and armature of relay 63, 20 and the armature and back contact of relay 254 controls the path to relay 30 by way of the conductor 72, holding this path open as long as the relay 254 is energized. When therefore the actuation of one of the relays 25 94 operates the relay 63, the operation of the relay 63 does not instantly close conductor 72 to energize relay 30 and move the finder sequence switch to position 8 where the upward movement of the cord selector brushes 30 is started. Instead, the closure of this energizing path for relay 30 is delayed until the relay 254 has had time to deenergize, after the interruption of its circuit at the back contact of relay 63, and release its armature to close the path of conductor 72. Under certain special circumstances in the 35 operation of the operator's selecting apparatus it is possible for the trip magnets associated with two operators' positions on the same cord selector frame, or for two trip magnets associated with same operator's position upon two different frames, to be momentarily operated. By providing the slow-acting relay 254 for delaying the advance of the finder sequence switch to its 40 next stage, the possibility of one finder circuit selecting two operators' positions, or of two finder circuits on different frames selecting the same operator's position, is prevented.

At the outset of the upward movement of the cord finder brush rod, the tripping levers of the various sets of brushes are brought simultaneously into operative position 45 with respect to the corresponding tripping yokes, and that set of brushes is tripped and made operative whose trip magnet is at the time energized. In the present instance, it is assumed that this is the trip magnet 20 associated with the terminals of the group of connecting cord circuits extending to the O operator's position.

Immediately after the set of brushes is tripped, the common operators' selecting 50 circuit is restored so as to be available for

the use of other cord finder switches. This is effected through the medium of a circuit that is completed by the grounding of the K segment of the cord finder commutator, this segment being so located as to be 50 engaged by its brush immediately after the tripping levers of the sets of brushes pass the associated tripping yokes. The circuit referred to extends from battery through the winding of relay 61, conductor 74, sequence switch contact 221 (7 to 8), conductor 80, cord finder commutator segment K and its corresponding brush to ground. Relay 61 in operating opens, at its left-hand back contact, the previously-traced circuit 55 by way of conductor 73 which, up to this time, has been holding energized the relay 95 at the O operator's position and the relays 93 and 94 corresponding to this position on the cord finder frame. The release 60 of the relay 94 deenergizes the corresponding trip magnet 22 and the common relay 63. The deenergization of the relay 93 re-establishes, subject to the release of relay 61, the control of other finder circuits over 65 the brush tripping mechanism of the associated cord finder frame.

Relay 61, in operating, closes a locking circuit for itself by way of conductor 73, sequence switch contact 218 (7 to 8), conductor 67, commutator segment M of the line finder and corresponding brush to ground. It also completes a circuit that extends from battery through the motor magnet and contact 204 (8) of the sequence 70 switch 200, conductor 75, right-hand front contact and armature of relay 61 to ground. The closure of this circuit moves sequence switch 200 out of position 8. In moving 75 out of position 8, the sequence switch opens its contact 218 (7 to 8), thus deenergizing relay 61 and again extending conductor 73 to the relay 54 and the conductors over which the operator's selection is effected. In closing its right-hand back contact upon 80 release relay 61 also restores the continuity of conductor 76 and makes it available for moving out of position 6 the sequence switch 85 of some other finder circuit which may be waiting for access to the operator's selecting circuit.

After the cord selector switch CS passes the brush-tripping position, it continues its upward movement until the brushes are stopped by engaging the terminals of one 90 of the connecting circuits that is not in use. The idle or busy condition of the connecting circuit is indicated by the presence or absence of high-potential battery on the test terminal 118 of each connecting circuit. When the brushes engage the terminals of an idle connecting circuit, a path 95 for the flow of current is completed from high potential battery 251 (see Fig. 4), through the winding of common protective 100

- relay 258, armature and back contact of that relay, lower back contact and armature of relay 259, conductor 128, armature and back contact of relay 420, contact 406 (1) 5 of the listening key sequence switch, conductor 88, test terminal 118 and brush 114 of the cord selector, conductor 99, finder sequence switch contacts 206 (8 to 9) and the winding of relay 37 to ground. Relay 37 10 thereupon attracts its armature and opens the previously traced locking circuit that has been holding relay 30 energized. Relay 30, in releasing its armatures, opens at its right-hand front contact and armature 15 the energizing circuit for the up-drive magnet 34, thus stopping the brushes of the cord selector switch in engagement with the terminals of the selected connecting circuit. In engaging its back contact, the right-hand 20 armature of relay 30 closes an energizing circuit for the motor magnet of the finder sequence switch which extends by way of cam 202 (8 to 9), back contact and right-hand armature of relay 30, cam 218 (8 to 25 9), conductor 67, and the M segment and corresponding brush of the line-finder commutator to ground. The closure of this circuit moves sequence switch 200 out of position 9, whereupon the switch continues to 30 move until it reaches position 14, where the talking circuit is completed at cams 213 and 214.
- An instant after the finder sequence switch leaves position 9, it closes a circuit 35 that extends from battery through the windings of relays 421 and 423 (see Fig. 4) in parallel, listening key sequence switch contacts 407 (1), left-hand back contact and armature of relay 422, conductor 87, cord 40 selector switch terminal 117 and corresponding brush 113, conductor 98, and finder sequence switch contacts 217 (9 $\frac{1}{2}$ to 14) and (9 $\frac{1}{2}$ to 11) to ground. Relay 421 in operating 45 closes a locking circuit for itself and relay 423 that extends by way of its upper front contact and armature, and sequence switch contact 405 (1 to 6) to ground. Relay 421 also closes a circuit that extends from battery through the motor magnet and 50 cam 403 (1) of the listening key sequence switch and lower front contact and armature of relay 421 to ground. The closure of this circuit causes the listening key sequence switch to move out of position 1, 55 and, in doing so, to open the test conductor 88 at sequence switch contact 406 (1), and also to open at sequence switch contact 407 (1) the path over which the relays 421 and 423 were first energized.
- 60 Relay 423, associated with relay 421, in operating closes a circuit that extends from battery through the winding of relay 422 and upper front contact and armature of relay 423 to ground. As a result relay 422, 65 prior to the moving of the listening key se-
- quence switch out of position 1, has disconnected conductor 87 from connection with battery by way of sequence switch contact 407 (1) and the windings of relays 421 and 423, and has connected it with an alternative 70 path to battery by way of the left-hand front contact of relay 422 and resistance device 424. When the listening key sequence switch reaches position 2, an additional path to ground for holding the relay 422 energized, is closed by way of sequence switch contact 412 (2 to 7).
- The energization of relay 423 at the instant the cord is seized also brings about the closure of a circuit that extends from battery through the winding of the common 80 relay 259, conductor 129, and lower front contact and armature of relay 423 to ground. Relay 259 in operating opens at its lower armature and back contact the circuit over 85 which the potential of the high voltage test battery 251 is supplied to the test conductors 128 of all of the connecting cords of the position. Thus the electrical condition which permits a connecting cord to be 90 seized by a cord selector is withdrawn from the selected cord and also from its associated cords at the instant of seizure, and is not re-applied to such of the cords as may be in condition to be selected until the common 95 relay 259 is de-energized. The de-energization of relay 259 occurs when the relays 421 and 423 are released by the opening of their locking circuit at cam 405 when the listening key sequence switch moves beyond position 6. 100
- When the listening key sequence switch 400 is moved out of position 1, in the manner described above, it continues its movement until it reaches position 7. In position 7 the cams 408, 409, 410 and 411 of 105 the listening key sequence switch interrupt the talking strands of the connecting circuit and include between their severed ends a loop that has connection by way of conductors 135 and 136 with the operator's telephone set 147. This puts the operator in communication with the calling subscriber. At the same time the operator is informed of the identity of the connecting cord over 110 which the call is being extended by the flashing of the lamp 161 associated with that cord, the circuit for illuminating this lamp extending from battery through the outer back contact and armature of relay 500, lamp 161, sequence switch contact 413 (7), 115 and interrupter 162 to ground.
- At this particular time the operator's sequence switch 300 is in position 17, or moving to that position. When the position was selected the operator's sequence switch was 120 standing in position 1 and the relay 91 was inert, thus providing a path for the energization of the relay 92, the operation of which relay when an operator's position is 125 to be selected serving to mark that particu- 130

lar position as being unengaged or selectable. When the position is selected, the relay 95 is operated in the manner previously described. In operating, the relay 95 closes a circuit that extends from battery through the motor magnet and cam 302 (1) of the operator's sequence switch, right-hand front contact and armature of relay 95, and left-hand front contact and armature of relay 125 to ground. The relay 125 at this time is operated, as its energizing path is completed by way of local contacts 127 of the operator's telephone jack 126, which contacts are closed when the operator is at her position and has her telephone plug inserted in the telephone jack. As a result of the closure of the circuit traced above, the operator's sequence switch 300 is moved out of position 1, thus opening the energizing path of relay 92 in sequence switch contact 303 (1) and making the position unselectable. The next resting position of the operator's telephone sequence switch 300 is position 4; but as relay 125 is energized, the motor magnet has an energizing circuit in this position by way of sequence switch contact 302 (4) and the right-hand front contact and armature of relay 125 to ground, and consequently the sequence switch moves on to its next resting position 17. The sequence switch remains in position 17, keeping the operator's position unselectable, until at a later stage in the operation the switch 192 is operated in any suitable manner to close its contacts. Switch 192 corresponds to the upper armature of relay 192 of application to S. B. Williams, Jr., Serial No. 180,634 filed July 14, 1917. At this time a circuit is closed that extends from battery through the motor magnet and cam 302 (17) of the operator's telephone sequence switch and closed contacts of switch 192 to ground. The closure of this circuit permits the sequence switch to move from position 17 to position 1, thus rendering the operator's position again available for receiving calls.

The operator's position is also rendered unselectable when the operator's telephone set is connected with one of the connecting circuits. This is effected through the medium of the relay 91. When the listening key sequence switch 400 of any of the connecting circuits of the operator's position is moved to position 7 to bring the operator's telephone set into connection with the corresponding circuit, an energizing path is completed that extends from battery through the winding of relay 91, conductor 137, and listening key switch contact 404 (2 to 9) to ground. The completion of this circuit causes the relay 91 to attract its armature and interrupt the path over which the relay 92 is adapted to be energized, thus preventing the operation of the associated selection controlling relays 77.

The removal of the telephone plug from the operator's telephone jack 126 when the operator leaves her position, also renders the position unselectable. When the plug is removed, the breaking of the circuit at the local contact 127 causes relay 125 to become inert and release its armatures. This closes a circuit that extends from battery through the motor magnet and cam 302 (1) of the operator's telephone sequence switch, and to ground by way of the right-hand back contact and armature of relay 125. In moving out of position 1 as the result of the closure of this circuit, the sequence switch interrupts the energizing path for the relay 92 in sequence switch contact 303 (1), thus preventing the operation of the corresponding selection controlling relays 77 when a connection is to be extended.

Reference has heretofore been made to the operation of the common relay 259 which is energized to remove the test condition from the selected connecting cord and all of its associated connecting cords at the instant the cord is seized. This relay 90 when it operates, also acts to complete a circuit that extends from battery through the winding of relay 91 and the winding of relay 193 in parallel, and thence to ground by way of the upper front contact and armature of relay 259. Relay 193 in operating, closes a circuit from battery through the motor magnet and contact 304 (1) of the operator's telephone sequence switch, and front contact and armature of relay 193 to ground. The closure of this circuit safeguards the operator's telephone sequence switch from standing or stopping in position 1 from the instant the cord circuit is seized. Relay 91 in operating insures the inaccessibility of the operator's position at this time by opening the path over which relay 92 must be energized.

When the operator has been put into communication the calling subscriber by the movement of listening key sequence switch 400 to position 7, as already described, and when the operator has learned the number of the line that is wanted, the connection may be completed by inserting calling plug 425, in which, in the present instance, the connecting circuit is represented as terminating, into the spring jack 142 of the calling subscriber's line. Instead of a plug and spring jack, any other of the well-known switching devices or mechanisms for establishing connection between a connecting circuit and a telephone line may obviously be employed. In the present instance, the connection-extending means is represented as a cord circuit provided with a repeating coil 426, answering and calling supervisory relays 427 and 428, respectively, and a switch 429 for applying ringing current from the source 430 to ring the bell at the 130

called subscriber's station D. As all of these parts may have their usual functions and may operate in the usual way, a description of them and of the exact manner 5 in which the cord circuit is organized is thought to be unnecessary.

When the calling plug 425 is inserted in the called line spring jack, an energizing circuit is completed that includes serially 10 the windings of the connecting cord relays 420 and 431 and the cut-off relay 11² of the called line. The cut-off relay 11² may have its usual function of disconnecting the line relay 12², thus depriving the 15 line of control over the calling apparatus. The relay 420 in operating interrupts at another point the path of the test conductor 88, thus keeping the cord circuit unselectable while the plug 425 is in the spring 20 jack of the called line. The relay 431 at its upper back contact breaks the connection of the tip of the plug with the conductor 133, which may extend to the test winding of the operator's telephone set, and 25 at its upper front contact closes the tip strand of the connecting cord to complete the talking circuit. The relay 431 in operating also closes a circuit that extends from battery through the winding of the relay 30 and the lower front contact and armature of relay 431 to ground. The relay 500 at its right-hand armature and back contact interrupts the circuit of the flashing call lamp 161 and extinguishes the lamp. 35 At its inner left-hand armature and front contact, the relay 500 closes a locking circuit for the holding relay 422 that extends by way of the right-hand front contact and armature of that relay. The relay 500 also 40 closes a circuit that extends from battery through the motor magnet and contact 402 (7) of the listening key sequence switch, outer left-hand front contact and armature of relay 500, and lower back contact and 45 armature of relay 421 to ground, the relays 421 and 423 having been released by the opening of their locking circuit at cam 405 when the listening key sequence switch moved beyond position 6. The listening 50 key sequence switch moves out of listening-in position 7 as a result of the closure of this last-mentioned circuit, and comes to rest in position 15.

The termination of the conversation between the subscribers is indicated in the usual way by signals displayed when the supervisory relays 427 and 428 become inert, and disconnection is effected by withdrawing the calling plug 425 from the 55 spring jack 14². The withdrawal of the calling plug 425 interrupts the energizing circuit of the relays 431 and 420, and these relays release their armatures. The relay 431 in releasing breaks the energizing circuit of the relay 500, and that relay in re-

leasing closes a circuit that extends from battery through the motor magnet and cam 402 (15) of the listening key sequence switch, outer left-hand back contact and armature of relay 500, and lower back contact 70 and armature of relay 421 to ground. The listening key sequence switch thereupon moves out of position 15, and comes to rest in position 1. Relay 500 in releasing also opens at its inner left-hand front contact 75 and armature, the locking circuit of the holding relay 422, and that relay, in releasing, breaks the connection of conductor 87 with battery by way of the device 424. When current ceases to flow through conductor 87, the relay 30 of the finder circuit, which has been included in the path of current flow by way of conductors 87, 98, 50 and 53, and the finder sequence switch cams 217 and 212, releases its armatures. 80 This closes the circuit from battery through motor magnet and cam 202 (14) of the finder sequence switch, left-hand back contact and armature of relay 30, and armature and back contact of relay 37 to ground. This 85 moves the finder sequence switch out of the talking position 14.

When the finder sequence switch reaches position 15 a circuit is closed for the energization of the relay 30 that includes in parallel branches both windings of that relay. One branch of this circuit extends from battery through resistance 56, sequence switch contacts 217 (15 to 16) and (12 to 16) right-hand winding of relay 30, sequence switch 95 contacts 220 (15) and (11 to 16) to conductor 67; the other branch extends from battery, through the left-hand winding of relay 30, and sequence switch contacts 220 (15) and (11 to 16) to conductor 67, thence 100 both branches extend by way of conductor 67, and M segment and corresponding brush of the line-finder commutator to ground. Relay 30 in operating closes a branch path to ground for maintaining its energization, 105 this path extending from the right-hand winding of relay 30, by way of sequence switch contacts 216 (15 to 16), left-hand front contact and armature of relay 30, and armature and back contact of relay 37 to 110 ground. Relay 30 in operating also closes a circuit that extends from battery, through motor magnet and contact 202 (15) of the finder sequence switch, right-hand front contact and armature of relay 30, sequence 115 switch contact 218 (15), conductor 67, and M segment and corresponding brush of the line-finder commutator to ground. The completion of this circuit energizes the finder sequence switch 200 and causes it to move its 120 cams to position 16.

In moving out of position 15 the sequence switch opens at its 220 cam, the branch of the energizing path that includes the left-hand winding of relay 30, and also opens 130

the path to ground by way of conductor 67 and the M segment of the line-finder commutator; the energization of the relay being maintained in position 16 of the sequence switch by way of the branch that includes its right-hand winding, cam 216, left-hand contacts of relay 30, and resting contacts of relay 37. This circuit is held closed and relay 30 is kept energized until 10 the cord circuit through which the call was extended has returned to its normal position. When this occurs a circuit is closed that extends from high-potential battery 251, through the winding and contacts of 15 common relay 258 (see Fig. 4), armature and back contact of relay 259, conductor 128, armature and back contact of relay 420, sequence switch contacts 406 (1), closed when the cord circuit returns to normal, 20 conductor 88, cord selector contact 118 and corresponding brush 114, conductor 99, sequence switch contact 208 (16), right-hand armature and front contact of relay 30, sequence switch contacts 224 (9 to 17) and 25 (16), and winding of relay 37 to ground. The closure of this circuit energizes relay 37, which attracts its armature and opens the previously-traced holding circuit of the 30 relay 30. Relay 30 in releasing its armatures closes a circuit that extends from battery through the winding of down-drive magnet 62 of the line-finder switch, conductor 60, sequence switch contacts 223 (16 to 35 7) and (16 to 16 $\frac{1}{2}$), left-hand back contact and armature of relay 30, and armature and back contact of relay 37 to ground (the 40 energizing circuit of relay 37 having been interrupted at the right-hand front contact and armature of relay 30 when that relay released). As a result of the closure of this circuit, the brushes of the line-finder switch are returned to normal.

As the line-finder brushes reach normal, a circuit is closed that extends from battery 45 through the motor magnet and contact 204 (16) of the finder sequence switch, conductor 69, and Y segment and corresponding brush of the line-finder commutator to ground. When the finder sequence switch moves to position 17, as a result of the closure of the above traced circuit, a circuit 50 is completed that extends from battery through the winding of the down-drive magnet 35 of the cord selector, conductor 90, finder sequence switch contact 218 (17), conductor 67, and M segment and corresponding brush of the line-finder commutator to ground. The closure of this circuit returns the cord selector switch to normal; and as the brushes reach normal a circuit 55 is closed that extends from battery through the winding and contact 204 (17) of the finder sequence switch, conductor 31, and segment Y and corresponding brush of

the cord selector commutator to ground. 65 The closure of this circuit causes the finder sequence switch 200 to return to its normal or 1 position.

It will be remembered that when the finder switch makes connection with the calling line the sequence switch 200 is moved out of position 4, and that when the sequence switch reaches position 4 $\frac{1}{2}$, a circuit is closed by way of cam 212 and conductors 50 and 53 for energizing the cut-off relay 11 70 of the calling line and bringing about the release of the associated line relay 12. It may occasionally happen in the operation of the system that the line relay 12 will fail to release when the calling line is connected with, either on account of the sticking of the line relay itself, or on account of the failure of the cut-off relay to operate and open the energizing circuit of the line relay. The result of this ordinarily would be to 75 cause the starting of a plurality of finder switches, for the reason that as long as the line relay 12 has its armature attracted the circuit for the energization of the group relay 19 will be closed by way of the timing sequence switch contact 103 (18 $\frac{1}{2}$ to 1 $\frac{1}{2}$) as often as the timing sequence switch completes its cycle of rotation and the group relay 19, in turn, causes the closing of the starting circuit and the starting of another 80 finder switch. Each of these started finder switches, under the conditions assumed, would have its brushes stopped upon the terminals of the line whose line relay had failed to release, as the continued attraction of the line relay armature would maintain the calling test potential on the test conductor 253 of the associated line.

In order to prevent such improper operation, the present system is so organized that 85 when the test potential continues on a calling line at a time when it should be withdrawn, the improperly operated relay is deprived of control over the starting circuit, and a signal is given the switchboard attendant to inform him of the abnormal condition that exists, the calling test potential at the same time being removed from the test conductor of the line.

The manner in which this result is accomplished is as follows: Let it be assumed 90 that the movement of the finder sequence switch 200 to position 6 when the calling line is found, fails to bring about the release of the associated line relay 12. When 95 the finder sequence switch moves out of position 6 upon the finder circuit gaining access to the operator's selecting circuit, a circuit is closed that extends from the high potential test battery 251, the winding of 100 the common protective relay 250, the back contact and armature of that relay, left-hand front contact and armature of line re-

5 lay 12, test conductor 253, test terminal 47 and corresponding test brush 43 of the line finder, conductor 51, contacts 224 (1 to 8) and (6 $\frac{1}{2}$ to 8) of the finder sequence switch, conductor 260, and winding of relay 52 of the operator's selecting circuit to ground by way of the relatively lower potential battery. The completion of this circuit causes the energization of the relay 52. Relay 52 10 in operating closes a locking circuit for itself that extends from battery through the winding of relay 52, left-hand front contact and armature of that relay, conductor 71, finder sequence switch contact 218 (6 $\frac{1}{2}$ to 8), conductor 67, and the M segment and corresponding brush of the line finder commutator to ground.

15 The protective relay is so wound and adjusted that it is unresponsive to the current which normally flows through it in connection with the testing and seizing of a calling line, but responds to the increased current flow which occurs when a direct path to ground is established. The operation of the relay 52 referred to establishes such a path, the circuit extending from high potential battery 251, right-hand inductive winding of protective relay 250, right-hand back contact and armature of that relay, left-hand front contact and armature of the sticking line relay 12, conductor 253, terminal 47 and its corresponding brush 43, conductor 51, sequence switch contact 224 (1 to 8) and (6 $\frac{1}{2}$ to 8), conductor 260, left-hand front contact and armature of relay 52, conductor 71, contact 218 (6 $\frac{1}{2}$ to 8), conductor 67 and the M segment and corresponding brush of the line finder commutator to ground. The protective relay 250 attracts 20 its armatures, and at its right-hand armature and front contact completes a locking circuit for itself that extends to ground by way of normally closed contacts of key 501, and which also includes the left-hand non-inductive winding of relay 250 in series with the right-hand or inductive winding, the left-hand winding being a protective winding which is normally short-circuited in the right hand armature and back contact of the 25 relay. The closure of this locking path directly to ground from the windings of the relay 250 also serves to remove the high potential calling test condition from the test conductor of the associated line.

30 55 At the left-hand front contact and armature of relay 250 a circuit is closed including the lamp 502 and the winding of the relay 503. The lamp is therefore lighted, and the relay 503 by attracting its armature completes a circuit for actuating an alarm signal of any suitable sort. Furthermore, relay 250 in operating opens, at its left-hand armature and back contact, the path to ground by way of which the line relays 12 are able

35 to exercise control over their associated group relay 19. Therefore, when the timing sequence switch 100 completes its cycle and closes its contact 103 (18 $\frac{1}{2}$ to 1 $\frac{1}{2}$), the path to ground for the energization of the relay 19, which otherwise would be completed at 40 the right-hand armature and front contact of the sticking line relay, is open at the left-hand back contact and armature of the protective relay 250, and the sticking relay is thus prevented from operating relay 19 and 45 energizing the starting circuit to cause the starting of other finder switches. When the attendant, responding to the alarm signal, removes the abnormal condition and depresses the key 501, relay 250 is released, 50 thus opening the alarm signal circuit and closing the common lead to again give the line relays 12 of the associated group control over the starting circuit.

55 The system herein disclosed is also so arranged that when the test relay 52 (see Fig. 3) responds as a result of the failure of the line relay to release, it opens at its right-hand back contact and armature the path over which the finder circuit operates to select an available operator's position, and to close at its right-hand armature and front contact a circuit for moving the finder sequence switch 200 into position to cause the upward movement of the cord selector. As 60 the opening of the path at the right-hand armature and back contact of relay 52 has prevented the tripping of any of the magnets 20, 21, the cord selector elevator rises with its brushes out of engagement with the connecting circuit terminals, and at the end of its upward movement grounds the segment X of the cord selector commutator. The circuit completed by the grounding of this segment causes the sequence switch 200 to move to position 15 and then to position 65 16 where the relay 255 (see Fig. 2) is operated to light the trouble lamp 257. If the associated switch 256 is open at this time, the cord selector switch remains at its top or 70 "tell-tale" position. If the switch 256 is closed, the apparatus operates to return the line finder switch and the cord selector switch to normal. This organization has been disclosed in the drawings, and is here 75 referred to briefly because it supplements the present invention in taking care of the situation which arises when a line relay fails to release; but it has not been described in detail since it forms no part of the present 80 invention. A detailed description of the operation of this portion of the system is fully given in the copending application of S. B. Williams, Jr., Serial No. 180,633, filed 85 July 14, 1917, and assigned to the same as- 90 signee.

95 In order that the features to which this invention is directed may be fully and clearly

disclosed, they have been described in connection with certain features that are the subject of other copending applications assigned to the same assignee, such applications including the applications of S. B. Williams, Jr., Serial No. 75,328, filed January 31, 1916; Serial No. 75,329, filed January 31, 1916; Serial No. 180,634, filed July 14, 1917, and the application of F. A. Stearn, Serial No. 107,540, filed July 5, 1916. These features are the subject of claims in the applications mentioned above, and are not claimed in the present application.

What is claimed is:

- 15 1. The combination with a plurality of telephone lines, of means for altering the electrical condition of each line in calling, a plurality of finder switches, means actuated by the altered electrical condition of a calling line for starting one of said finder switches to make connection therewith and for bringing another finder switch into operative relation with said lines, means actuated by the establishment of connection between a finder switch and a calling line for restoring the calling line to its normal electrical condition, a test magnet associated with said finder switch, said test magnet being responsive to the altered electrical condition of the associated telephone line, and means controlled by said test magnet for preventing said calling line from starting other finder switches.
- 20 2. The combination with a telephone line, means actuated by said line in calling for altering the normal electrical condition thereof, a plurality of finder switches, means actuated by the altered electrical condition of a calling line for starting one of said finder switches and placing another of said switches in readiness to be started, means actuated in establishing a connection between said started finder switch and said calling line for restoring said calling line to its normal electrical condition, a test magnet associated with said finder switch, said test magnet being responsive to the failure of the calling line to be restored to normal condition when connection is established therewith, and means controlled by said test mag-

net for preventing the altered electrical condition of said calling line from starting other finder switches.

3. The combination with a telephone line, a plurality of finder switches responsive to the altered electrical condition of the line in calling for making connection with said line, means actuated by the establishment of connection with said line for restoring the normal electrical condition thereof, other finder switches actuated by a continuation of the altered electrical condition of the calling line after connection is made therewith, and means responsive to a continuation of said altered electrical condition after the establishment of connection for restoring the normal condition of said line and preventing the starting of other finder switches.

4. The combination with a telephone line, a plurality of finder switches, means actuated by said line in calling for causing one of said finder switches to make connection therewith, means actuated in making connection for altering the calling condition of said calling line, a test magnet associated with said finder switch responsive to a continuation of said calling condition after connection is made with the line, and auxiliary means controlled by said test magnet for preventing said continued calling condition from causing the starting of another of said finder switches.

5. The combination with a telephone line, a plurality of finder switches, means actuated by said line in calling for starting a finder switch and producing a test condition on said line to which said finder switch is responsive, means actuated by a finder switch in making connection with said line for restoring the test condition and finder-starting condition to normal, a test magnet associated with said finder circuit responsive to a continuation of said test condition after connection is made with the line, and auxiliary means actuated in the response of said test magnet for changing the test and finder-starting condition of said line.

In witness whereof, I hereunto subscribe my name this 15th day of March A. D., 1918.

EDWIN H. SMYTHE.
